UNITED STATES PATENT OFFICE.

WILLIAM A. JAMESON, OF NIAGARA FALLS, NEW YORK.

DESIGN FOR A HANDLE FOR SPOONS.

SPECIFICATION forming part of Design No. 27,202, dated June 15, 1897.

Application filed April 26, 1897. Serial No. 634,043. Term of patent 7 years.

To all whom it may concern:

Be it known that I, WILLIAM A. JAMESON, a citizen of the United States, residing at Niagara Falls, in the county of Niagara, State 5 of New York, have invented and produced a new and original Design for Handles of Spoons, &c., of which the following is a specification, reference being had to the accompanying drawings, showing a part thereof.

10 Figure 1 is a plan or elevation view of the front or obverse side of a spoon the handle of which embodies my design, the dotted lines showing how the handle may be applied to a fork; and Fig. 2 is a similar view of the 15 reverse or rear side of the spoon and handle.

The general outline of the handle is of the violin-shaped order. As the handle leaves the bowl it contracts slightly in the usual form, after which the sides run nearly parallel with each other for about one-third the 20 length of the handle, after which it expands and then contracts slightly, forming a graceful swell at *a*. This part of the handle is bordered both on the obverse and reverse 25 sides by elongated bead-like or fluted ornaments *b*, small and large alternately, leaving a raised burnished center *c* on front and a flat center on back. From this point the handle widens with long and distinct inward and out-

30 ward curves until near the widest part of the handle is reached, these curves forming, in connection with the scroll-like ornaments *d* both on front and back of handle, a very attractive border. From the point last men-

35 tioned the outline widens slightly, and then gradually curves inward in a succession of short inward and outward curves *e* until the apex is reached. These curves, in connection with the short fluted ornaments, which 40 extend inward and downward, form the border for the upper end of the handle. The ornaments, as described, form a continuous

border from point of handle where it joins the bowl to apex, leaving an unbroken raised burnished center extending almost the entire 45 length of the handle, which expands and contracts in a manner corresponding with the outline of the handle on the front or obverse side, the reverse side being flat. The ornaments give to the center a double shield-like 50 effect in the broadest part of the handle. The bead-like or fluted ornaments *b* extend also from the apex to and upon the widest portion of the handle on the obverse side. The whole is executed in what is known as 55 the "Baroc" or "Louis XIV" style of ornaments.

The essential features of this design, whether of the front or back face of the handle, consist of a violin-shaped outline having 60 scroll ornaments at the sides of its widest portions, bead-like ornaments, large and small, alternating at the sides of the narrow portion extending from the bowl to the scroll ornaments, inward and outward curves with 65 bead-like ornaments extending from the widest portion to the apex, a raised center on the obverse side extending nearly the full length of the handle, and the center of the reverse side flat.

70 What is claimed as new is—

1. The design for the handle of a spoon or similar article, as set forth.
2. In the design for the handle of a spoon or similar article, the design of the obverse 75 side of the handle, as set forth.
3. In the design of the handle of a spoon or similar article, the design of the reverse side of the handle, at set forth.

WILLIAM A. JAMESON. [L. S.]
